UNITED STATES PATENT OFFICE

2,609,788

MECHANISM FOR COATING INTERIOR OF
HOLLOW ARTICLESCharles A. Wulf, Indianapolis, Ind., assignor to
Ceramic Process Co., Indianapolis, Ind., a cor-
poration of Delaware

Application November 30, 1950, Serial No. 198,438

8 Claims. (Cl. 118—56)

1

The present invention relates to mechanism for coating interiors of hollow articles. The specific mechanism disclosed and described herein has been designed for uniformly coating the interior surfaces of a specific article; but it will be clear, as the description proceeds, that the mechanism of the present invention is equally applicable to other and radically different forms of hollow articles.

The primary object of the invention is to provide a mechanism through the use of which a large excess of fluent material, such as enamel, paint, or the like, may be flooded into an article to be coated, then most of the excess material may be returned to the reservoir from which it was drawn, and then the article may be so manipulated, as to achieve uniform distribution of the coating material throughout its interior surface, and to effect at least an initial drying and setting of the material during such manipulation. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is an end elevation of one portion of the mechanism constructed in accordance with the present invention, showing an article to be coated in operative position therein;

Fig. 2 is a front elevation thereof;

Fig. 3 is a fragmental, enlarged perspective view of the means for securing the article to be coated in place on the carriage of the mechanism;

Fig. 4 is an end elevation of another portion of the said mechanism, showing an article in operative position therein;

Fig. 5 is a fragmental perspective view, drawn to an enlarged scale, and showing an operative detail of the structure of Fig. 4;

Fig. 6 is a fragmental view of the operating parts shown in Fig. 4, the parts being in a different position of adjustment; and

Fig. 7 is a side elevational view, taken from the left of Fig. 4, the article to be manipulated having been removed from the mechanism.

Referring more particularly to the drawings, it will be seen that the portion of the mechanism illustrated in Figs. 1 to 3 comprises a frame 10 and a carriage 11, said carriage having a passage 12 therethrough, and being provided with aligned trunnions 13 and 14 respectively jour-

2

nalled in bearings 15 and 16 carried on the frame, the trunnion axis being transverse with respect to the axis of the passage 12. Collars 17 and 18 may be fixed to the projecting ends of the trunnions 13 and 14 to hold the carriage 11 against movement axially of said trunnions with respect to the bearings 15 and 16.

A container 19 for fluent material is closed except for an open mouth 20 at one end thereof. Rods 21 and 22 depend from diametrically opposite points on the carriage 11, and support a spanner strap 23 upon which the container 19 may rest. Wing nuts 24 and 25 threaded to the free ends of the rods 21 and 22, are adjustable to shift the spanner 23 axially of said rods, thereby to press the open mouth 20 of the container 19 into sealing engagement with the carriage 11 in communicating registry with one end of the passage 12. The container mouth or the cooperating surface of the carriage 11 may be made of, or coated with, resiliently deformable material, or a gasket may be interposed between the container mouth and the carriage, whereby a liquid-tight joint is produced between said carriage and said container mouth.

The article 26 whose interior is to be coated is formed with opposed openings 27 and 28. Rods 29 and 30 project upwardly from diametrically opposite positions on the upper surface of the carriage 11, the free ends of said rods being spanned by a strap 31 held in place by adjustable nuts 32 and 33. A closure plate 34 is adapted to cooperate with, and seal, the opening 28 of the article 26. As shown, the specific article 26 is so formed that its opening 28 is disposed in a plane angularly related to the plane of its opening 27. For this reason, the closure 34 is provided, at its edge engageable with the upper side of the opening 28, with a pair of depending fingers 35 to hook over the edge of said opening; and the closure 34 is supported from the strap 31 by means of a screw 36, threadedly penetrating said strap, and engaging said closure through the medium of a ball joint 37.

The container 19 being filled with a quantity of coating material largely in excess of that necessary for coating the internal surface of an article 26, is positioned in the manner clearly illustrated in Figs. 1 and 2. Now, an article 26 is placed on the upper surface of the carriage 11, with its opening 27 in communicating registry with that end of the passage 12 opposite that with which the container communicates. In any suitable manner, a liquid-tight joint is formed between the article 26 and the carriage 11; and the closure 34 is engaged with the open end 28 of the article 26, the

screw 36 being turned down to provide a liquid-tight seal for the opening 28.

Now, the carriage 11, together with the container 19 and the article 26, will be turned about the axis of the trunnions 13 and 14, through 180°, whereby all of the coating material in the container 19, or a quantity sufficient to fill completely the interior of the article 26, will be discharged from the container into said article. Immediately thereafter, the carriage 11 will be returned to its illustrated position, whereupon the excess of coating material, beyond that required to coat the internal walls of the article 26, will be returned to the container 19.

Now the article 26 is removed from the carriage 11, and placed in the holder 50 forming a part of the remaining portion of the mechanism of the present invention, illustrated in Figs. 4 to 7 inclusive.

This latter portion of the mechanism comprises a frame 40 which may be integral with or separate from the frame 10. Bearings 41 and 42 carried by the frame 40 support a shaft 43 for rotation about its own axis. Preferably, the axis of the shaft 43 will be inclined at an angle of approximately 45° to the vertical, in the manner shown in the drawings.

An electric motor 44, or other suitable power-delivering means, will be mounted upon the frame 40, and, through a belt 45, chain, or gear train, will be connected to drive a speed reducer 46 drivingly connected to the shaft 43.

At its end remote from the speed reducer, the shaft 43 carries a yoke 47 comprising parallel, separated arms 48 and 49.

A holder 50 is supported from the yoke 47, said holder being suitably shaped to receive and support an article 26. Obviously, for handling different articles, the holder 50 may assume different shapes. In the illustrated form, a strap 51 is hinged at 52 to overlie an article 26 resting in the holder 50; and suitable clamp means 53 will be provided for securing the strap 51 in retaining association with the holder 50.

Trunnions 54 and 55 project oppositely from the holder 50 to support the same, said trunnions being journalled in suitable bearings carried by the arms 48 and 49 respectively of the yoke 47. The trunnion 54 projects beyond its bearing and carries, outboard, a beveled gear 56.

Supported upon suitable brackets carried by the yoke arm 48, aligned bearings 57 and 58 provide a journal mounting for an auxiliary shaft 59 upon an axis parallel with, but radially removed from, the axis of the shaft 43. At one end, the shaft 59 carries a beveled gear 60 meshing with the gear 56, and at its opposite end, said shaft carries a pin wheel 61 from which project four equally spaced pins 62.

An abutment block 63 is carried upon a lever 64 pivotally mounted at 65 on the frame 40. Intermediate its ends, the lever 64 is provided with a clamp bolt 66 passing through a slot 67 in a plate 68 fixed to the frame 40. A lever 69, pivoted at 70 on the frame 40, is connected by a link 71 with the lever 64, said link being pivoted at 72 to the lever 69 and at 73 to the lever 64. Thus, the block 63 may be adjusted toward and away from the orbit of movement of the pin wheel 61.

When an article 26, after having been flooded with coating material in the portion of the mechanism illustrated in Figs. 1 to 3, is mounted in the holder 50 (which may preferably include an angle bar 76 extending longitudinally of such

article, as clearly shown in Fig. 4), it will be seen that its openings 27 and 28 are entirely unobstructed. When the shaft 43 is now rotated, the article 26 will be given a wobbling movement, with respect to a line joining its openings 27 and 28. As the pin wheel 61 passes the abutment 63, one of its pins 62 will strike said abutment, in the manner suggested in Fig. 5, whereby the shaft 59 will be turned 90° about its own axis. The gears 60 and 56 being of equal pitch diameters, the holder 50 will be turned correspondingly through 90°, thus shifting the holder, and the article 26 carried thereby, from the position of Fig. 4 to the position of Fig. 6. In the position of Fig. 6, a blast of hot air is directed through the openings 27 and 28 of the article 26 from a blower 74; while, in the position of Fig. 4, a blast of unheated air is directed through said openings from a fan 75.

Upon its next revolution, the yoke 47 will again carry the pin wheel 61 past the abutment 63, again to turn the holder 50 through 90°, thus bringing the article 26 into a position 180° removed from the position of Fig. 4, so that the blast from the fan 75 again is directed through the openings 27 and 28. Upon the next revolution of the yoke, the pin wheel 61 will again be actuated to shift the article 26 into a position 180° removed from that of Fig. 6; while the next revolution of the yoke will return the article 26 to the position of Fig. 4.

I claim as my invention:

1. Mechanism for coating interiors of hollow articles, comprising a carriage mounted for oscillation about a horizontal axis, said carriage being provided with a passage therethrough formed on an axis transverse to said carriage axis, a container for fluent coating material, said container being closed except for an open mouth, means for securing said container to said carriage with its open mouth in communicating registry with one end of said passage, means on said carriage for securing to said carriage a hollow article having an opening therein, with said opening in communicating registry with the other end of said passage, a carrier journalled for rotation about its own axis, means for driving said carrier, holder means mounted on said carrier for rotation about an axis transverse with respect to the axis of rotation of said carrier, said holder means being adapted to receive and support such hollow article with the axis of said article opening transverse to the axis of rotation of said holder means, abutment means fixed with respect to the axis of rotation of said carrier, and driver means moving with said carrier and operatively connected to drive said holder means about its axis, said abutment means being positioned in the path of said driver means to actuate the latter upon rotation of said carrier.

2. Mechanism for coating interiors of hollow articles, each such article being provided with two opposed openings into its hollow interior, such mechanism comprising a carriage mounted for oscillation about a horizontal axis, said carriage being provided with a passage therethrough formed on an axis transverse to said carriage axis, a container for fluent coating material, said container being closed except for an open mouth, means for securing said container to said carriage with its open mouth in communicating registry with one end of said passage, means on said carriage for securing to said carriage such an article with one of said article openings in communicating registry with the other end of said passage.

said last-named securing means including a closure for the other of said article openings, a carrier journalled for rotation about its own axis, means for driving said carrier, holder means mounted on said carrier for rotation about an axis transverse to the axis of rotation of said carrier, said holder means being adapted to receive and support such hollow article with both of its openings unobstructed, abutment means fixed with respect to the axis of rotation of said carrier, and driver means moving with said carrier and operatively connected to drive said holder means about its axis, said abutment means being positioned in the path of said driver means to actuate the latter upon rotation of said carrier.

3. Mechanism for coating interiors of hollow articles comprising a carrier journalled for rotation about its own axis, means for driving said carrier, holder means mounted on said carrier for rotation about an axis transverse with respect to the axis of rotation of said carrier, said holder means being adapted to receive and support such an article, abutment means fixed with respect to the axis of rotation of said carrier, and driver means moving with said carrier and operatively connected to drive said holder means about its axis, said abutment means being positioned in the path of said driver means to actuate the latter upon rotation of said carrier.

4. Mechanism for coating interiors of hollow articles, each such article being provided with two opposed openings into its hollow interior, such mechanism comprising a carrier journalled for rotation about its own axis, means for driving said carrier, holder means mounted on said carrier for rotation about an axis transverse with respect to the axis of rotation of said carrier, said holder means being adapted to receive and support such an article with its openings unobstructed and with a line joining its openings transversely arranged with respect to the axis of rotation of said holder means, abutment means fixed with respect to the axis of rotation of said carrier, driver means moving with said carrier and operatively connected to drive said holder means, said abutment means being disposed in the path of said driver means to actuate the latter, upon engagement of said driver means with said abutment means, to turn said holder means through 90° about its own axis, means arranged to direct a fluid blast through the openings of such an article carried by said holder means when said holder means is in either of two positions 180° removed from each other, and other means

for directing a fluid blast through the openings of such an article when said holder is in either of two positions 90° removed from said first-named positions.

5. The mechanism of claim 4 wherein one of said fluid blast means delivers a stream of hot air while the other of said fluid blast means delivers a stream of unheated air.

10 6. In a device of the class described, a carrier, means mounting said carrier for rotation about an axis, a holder, trunnion means supporting said holder on said carrier for rotation about an axis transverse of the axis of rotation of said carrier, a shaft journalled on said carrier for rotation about an axis parallel with the axis of

15 rotation of said carrier, gear means connecting said shaft to drive said holder, a pin wheel carried on said shaft, and abutment means, fixed with respect to the axis of rotation of said carrier and positioned in the path of said pin wheel.

20 7. In a device of the class described, a frame, a shaft mounted in said frame for rotation about its own axis, motor means mounted on said frame, a driving train including a reduction gear connecting said motor means to drive said shaft,

25 a yoke carried by said shaft, a holder, trunnion means supporting said holder, said trunnion means being mounted on said yoke for rotation upon an axis spanning said yoke, an auxiliary shaft, means supporting said auxiliary shaft from said yoke adjacent an arm of said yoke for rotation about an axis parallel with the axis of said first-named shaft, a drive train connecting said auxiliary shaft to drive said trunnion means, a pin wheel carried by said auxiliary shaft, and abutment means carried on said frame in the path of said pin wheel.

30 8. The device of claim 7 in which said first-named shaft is mounted on an axis inclined at approximately 45° to the vertical, said trunnion axis being substantially horizontal.
